[57] CLAIM

The ornamental design for a seal-spout for container, as shown.

DESCRIPTION

FIG. 1 is a top plan view of a blank of material forming a seal-spout embodying my new design;

FIG. 2 is a top plan view of a seal-spout formed from the blank of FIG. 1, as it would appear in folded, sealing condition;

FIG. 3 is a side elevational view thereof, as it would appear in unsealed, partially erected condition on a container top;

FIG. 4 is a side elevational view thereof, shown in fully erected, open condition; and,

FIG. 5 is a top perspective view thereof.

The container included in FIGS. 3-5 is shown for illustrative purposes only, and forms no part of the present invention.
